Primary Examiner — Sheryl Lane*Assistant Examiner* — Aula Soroush(74) *Attorney, Agent, or Firm* — Dorsey & Whitney LLP(57) **CLAIM**

We claim the ornamental design for an oral irrigator handle, as shown and described.

DESCRIPTION

FIG. 1 is an isometric view of an oral irrigator handle with a tip shown in dashed lines for environment.

FIG. 2 is a front isometric view of the oral irrigator handle of FIG. 1.

FIG. 3 is a front elevation view thereof.

FIG. 4 is a rear elevation view thereof.

FIG. 5 is a right side elevation view thereof.

FIG. 6 is a left side elevation view thereof.

FIG. 7 is a top plan view thereof; and,

FIG. 8 is a bottom plan view thereof.

The broken lines in FIGS. 2-8 indicate features of the oral irrigator handle that form no part of the claimed design. The broken line showing of the tip in FIG. 1 illustrates environment and forms no part of the claimed design.
